CLAIM

The ornamental design for a roughened glove unit for grasping wet infants, as shown and described.

DESCRIPTION

FIG. 1 is a front elevational view of the novel roughened glove unit for grasping wet infants, the opposite view being a mirror image thereof;

FIG. 2 is a top plan view thereof;

FIG. 3 is a bottom plan view thereof;

FIG. 4 is a left side elevational view thereof; and,

FIG. 5 is a right side elevational view thereof.
